UNITED STATES PATENT OFFICE.

HENRY M. SCHNABEL, OF GREENWICH TOWNSHIP, FAIRFIELD COUNTY, CONNECTICUT.

VALVE-LIFTER FOR AUTOMOBILES.

1,279,017.

Specification of Letters Patent. Patented Sept. 17, 1918.

Application filed September 18, 1916. Serial No. 119,845.

To all whom it may concern:

Be it known that I, HENRY M. SCHNABEL, a citizen of the United States, and resident of the township of Greenwich, in the county 5 of Fairfield, State of Connecticut, have invented certain new and useful Improvements in Valve-Lifters for Automobiles, of which the following is a specification.

The device, the subject of this invention, 10 is intended as a means for lifting a valve and valve guide-rods or valve-stem of a gasolene engine, for the purpose of removing the pin and spring tension so that the valve may be lifted out of its position or seat to allow a 15 grinding of the valve and valve seat or either.

This device also contains means for lifting 20 a valve against the spring tension, if by accident, the valve is dropped to a very great extent before the spring is removed.

The following is what I consider a good means of carrying out this invention, and the accompanying drawings should be considered in view of the specification which 25 follows:

In the drawings.

Figure 1 is a perspective view of my valve lifter.

Fig. 2 a plan view.

30 Fig. 3 a perspective view of a modification in which the valve lifter is provided with an inserting rod and support.

Fig. 4 a modification wherein the lifter is operated by a pull movement.

35 Fig. 5 a modification wherein the valve head is removable and other heads may be substituted.

Fig. 6 shows in elevation one of the removable heads.

40 Fig. 7 shows a still further modification.

Fig. 8 shows in perspective one end of the device shown in Fig. 7.

Fig. 9 shows my valve-lifter retaining a valve spring elevated.

45 Fig. 10 shows the operation of the other end of the device in elevating a spring.

Similar reference numerals indicate like parts in all of the figures where they appear.

My valve-lifter consists of a body portion, 50 1, which may be of a width or thickness desirable to provide sufficient strength and length for convenient and satisfactory operation.

At the wedged end, the left end of the 55 lifter, as shown in the drawings, I provide a plurality of blocks 2 and 3, each formed

integral with the body 1, and connected thereto by an enlarged portion 4.

Between the two locks is a recess 5, into which the valve stem or guide may be allowed to pass and it will be noted that each block is tapered in three different planes.

The longer tapers 6 and 7, assure that the valve lifter will be forced continually toward the valve stem and that it will engage thereon. The upper tapers 8 and 9, are adapted to pass under the washer and to force it upward, the washer riding up the tapers 8 and 9, and resting upon the flat 65 portion 10 and 11.

The lower tapers 12 reduce the area or length of the sides 6 or 7, and ride upon the valve stem guide, which guide rests upon the portion 13, and the difference between the width at the point of the tapers and the 70 width from 11 to 13, is sufficient to lift the spring an extent to allow the pin to be removed.

Should the washer drop after the pin is removed, I insert under the washer the 75 prongs 14 and 15, shown formed at the opposite end of the body 1, and as these prongs are turned upward, a downward pressure upon the left or block bearing end of the body member 1, will lift the washer to a 80 desirable extent. Between the prongs 14 and 15, a recess 16, is formed into which the valve stem may pass.

I have found in some instances that it 85 may be difficult to insert my valve-lifter or any valve-lifter, and therefore I have provided a guide member 17, having a step or block 18, which is intended to engage the valve guide block. When so engaged the valve lifter 19, is placed upon the flat upper portion of the guide 17, and between the guide posts 20 and 21 and an inward pressure upon the ball 22, will force the valve lifter 19, into position under the 90 spring disk or washer. When pressing the ball end 22, the fingers may be engaged upon the posts 20 and 21, and these posts will materially assist in the operation of 95 inserting the valve lifter.

A method of operation preferred by some 100 is to pull the valve lifter into position, to accomplish this it is necessary to provide a hook which is adapted to engage the valve-rod and such a construction is shown in Fig. 4. The hook is formed with a recess 105 23, and back of this recess is a block 24, upon which the spring disk will rest. Upon 110

the prong 25, and the body 26, of the valve holder are tapered blocks which operate in the same manner as do the blocks 2 and 3, in Fig. 1, with the exception that the taper is 5 toward the body portion 26 of the valve holder, this being necessary as this device is intended to be pulled outward to engage under the valve disk.

The device shown in Figs. 5 and 6, is similar in construction to that shown in Fig. 1, with the exception that the member 30, carrying the blocks 2 and 3, is removable and is engaged into the body member 31, by a rabbet or dove-tail 32. With this device 15 blocks of any desired height may be employed or blocks of a different shape may be attached. It will be noted in all of my constructions that the operation is that of a wedge or a plurality of wedges inserted 20 by being forced under the valve spring disk and that whereas the prongs 14 and 15, elevate the disk the blocks 2 and 3, retain the disk in an elevated position.

In the construction shown in Fig. 7, the 25 pronged end is provided with a plurality of transverse projections 34, one projection being formed integral with each prong. These projections serve as a means for receiving and temporarily retaining the valve spring 30 disk.

In this figure I also show serrations 35, which engage upon the valve rod guide. These serrations form a plurality of steps making my device operable with valve stems and guides of different heights. They also determine the extent to which the spring washer will be elevated. 35

Other modifications may be made within the scope of the appended claims without departing from the principle or sacrificing 40 the advantages of the invention.

Having carefully and fully described my invention what I claim and desire to secure by Letters Patent is:

1. A valve lifter comprising a wedged end 45 having a plurality of blocks and a recess between the said blocks and adapted to wedgingly lift a valve spring and retain it in an elevated position, as and for the purpose set forth.

2. A valve spring lifter consisting of a plurality of blocks in alinement and having a recess between them, each said block being tapered upon three sides and adapted to be inserted between a spring washer and a 55 valve guide to be temporarily retained by the pressure of said spring.

Signed at New York city, this 31st day of August, 1916.

HENRY M. SCHNABEL.
